UNITED STATES PATENT OFFICE.

WILLIAM F. KUCK, OF ETNA GREEN, INDIANA.

BRUSH.

1,275,049.

Specification of Letters Patent. Patented Aug. 6, 1918.

Application filed April 6, 1918. Serial No. 227,054.

To all whom it may concern:

Be it known that I, WILLIAM F. KUCK, a citizen of the United States, residing at Etna Green, in the county of Kosciusko and State of Indiana, have invented certain new and useful Improvements in Brushes; and I do hereby declare the following to be a full, clear, and exact description of the invention, such as will enable others skilled in the art to which it appertains to make and use the same.

The invention relates to improvements in brushes.

The object of the present invention is to improve the construction of brushes and to provide a simple, practical and comparatively inexpensive wheeled fountain brush designed for painting fences, white-washing and coating wire and other fences to protect the same from rust, decay and the like.

A further object of the invention is to provide a brush of this character adapted to move rapidly over the ground so that a relatively large amount of fencing may be coated or painted in a comparatively short time.

With these and other objects in view the invention consists in the construction and novel combination and arrangement of parts hereinafter fully described, illustrated in the accompanying drawings and pointed out in the claims hereto appended, it being understood that various changes in form, proportion and minor details of construction may be resorted to without departing from the spirit or sacrificing any of the advantages of the invention.

In the drawing

Figure 1 is a side elevation of a wheeled fountain brush constructed in accordance with this invention.

Fig. 2 is a horizontal sectional view on the line 2--2 of Fig. 1.

Fig. 3 is a detail sectional view taken longitudinally of the back of the brush.

Fig. 4 is a detail view of the shoe or runner.

Fig. 5 is a detail sectional view illustrating the construction of the clips for securing the brush to the wheeled frame.

Like numerals of reference designate corresponding parts in the several figures of the drawing.

In the accompanying drawing in which is illustrated the preferred embodiment of the invention, 1 designates a frame preferably

arranged vertically and consisting of a bicycle frame having front and rear wheels 2 and 3, the front wheel being mounted in a front fork 4 having a steering handle 5 but the construction of the wheeled frame may of course be varied. The wheeled frame carries a vertical brush consisting of fiber 7 secured between vertical plates 8 by bolts 9 or other suitable fastening devices to enable the fiber to be renewed when worn but any other suitable brush material may of course be employed. The brush is secured at right angles to the frame 1 by clip 10 piercing the brush and embracing the bars of the frame and provided with clip plates 11 and cross bolts 12. The clip plates are secured to the sides of the approximately U-shaped clip 10 by nuts 13 or the ends of the sides of the clips may be clenched, 75 against the clip plates.

The cross bolt 12 which is provided with a nut 14 is adapted to cause the sides of the clip 10 to engage tightly the frame bar embraced by it.

The brush which is designed for coating wire fences with coal tar or other preservative for painting and white-washing fences is supplied with the desired liquid by a vertical feed pipe 15 carrying a tank or reservoir 16 and provided at intervals with branch pipes or tubes 17 extending from the vertical feed pipe to the fiber of the brush and provided with suitable controlling valves 18. The vertical tube or feed pipe is connected 90 with the brush by a clamp 19 composed of substantially cylindrical portions to embrace the vertical pipe, a shank or stem 20 and approximately L-shaped arms 21 conforming to the configuration of and bolted or otherwise secured to the back of the brush. The clamp 19 is preferably constructed of a single piece of material bent to form the circular cylindrical portion and extended forwardly therefrom to form the stem or shank which is composed of two plies or thicknesses, the material being spread or bent outwardly at the front end thereof to form the said arms 21. The branch tubes 17 are preferably arranged at a slight 100 inclination and the valves will control the feed of the liquid to the brush.

The tank or reservoir may consist of a receptacle of any desired character. The brush is provided at its middle portion with a suitable handle 22 and it is equipped at its lower portion with a runner or shoe 25.

BEST AVAILABLE COP

1,275,049

The handle is preferably constructed of sheet metal or similar material, and it is arranged horizontally and located below the top bar of the frame of the device.

5 Any other form of handle may of course be employed and the said handle 22 is adapted to be grasped with one hand while the steering handle 5 of the frame 1 is held in the other hand. This will enable the machine to be moved rapidly and accurately along a fence and in coating a wire fence substantially the inner and outer faces of the fence will be painted or otherwise coated as the brush material will extend through the fence and around the wire.

10 The shoe 23 which is constructed of suitable material is adapted to rest upon the ground and it has a curved upwardly extending front portion 24 to enable it to readily pass over rough surfaces. The shoe or runner is preferably secured to the lower end of the vertical feed pipe and for this purpose it is equipped with upwardly extending jaws or flanges 25 adapted to embrace the lower end of the vertical tube at opposite sides thereof and one of the projecting flanges is equipped with a set screw 26 clamping the feed tube or pipe. By this construction the runner or shoe is detachably secured to the lower end of the brush and is adapted to support the brush out of contact with the ground.

15 The brush is located at a point intermediate of the ends of the frame 1 and the device is adapted to be moved rapidly along the fence or other surface to be coated and the feed of the liquid may be controlled to correspond with the speed of the brush in traveling over the ground.

What is claimed is:—

1. A device of the class described including a wheeled frame, a vertical brush mounted on the wheeled frame at one side thereof and projecting laterally therefrom, a vertical feed pipe provided with branch tubes extending to the said brush and a receptacle carried by the upper end of the feed pipe. 40

2. A device of the class described including a portable frame, an upright laterally projecting brush carried by the frame, means for supplying the brush with a liquid and a runner or shoe located at and supporting the lower end of the brush. 50

3. A device of the class described including a portable frame, an upright brush carried by the frame, a vertical feed pipe connected with the brush and provided with branch pipes for supplying liquid to the said brush, and a runner having lugs or flanges 60 located at opposite sides of the lower end of the feed pipe and provided with means for clamping the same. 55

4. A device of the class described including a frame provided at the front with a steering wheel having a handle, an upright brush secured to the frame, a handle secured to the frame, said brush extending laterally from the frame, a runner supporting the lower end of the brush and means for 70 supplying the brush with a liquid. 65

In testimony whereof I affix my signature in presence of two witnesses.

WILLIAM F. KUCK.
